WILKINSON

HANDLE FOR SPOONS, &c.

No. 20,119.

Patented Aug. 26, 1890.

UNITED STATES PATENT OFFICE.

WALTER WILKINSON, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 20,119, dated August 26, 1890.

Application filed December 23, 1889. Serial No. 334,749. Term of patent 7 years.

To all whom it may concern:

Be it known that I, WALTER WILKINSON, a citizen of the United States, residing at Providence, in the county of Providence and

5 State of Rhode Island, have invented and produced a new and original Design for the Ornamentation of the Handles of Spoons, Forks, Knives, &c.; and I do hereby declare the following specification, taken in connection with 10 the accompanying photographic illustration, forming a part of the same, to be a description thereof.

This design relates to the ornamentation of 15 the handles of spoons, forks, knives, ladles, &c.; and it consists in the features herein-
after described and claimed.

Around the edge or outline of the handle and upon the face thereof is arranged a series 20 or row of beads or half-balls A, and upon the shank of the handle and between the beads or half-balls are located several raised ribs B,

which extend upwardly in a direction longitudinally of the handle. Two of these ribs 25 b are shorter than the others, and are surrounded by beads or half-balls C.

Upon the upper portion of the handle, near its end, is arranged a shell-like ornament D.

What I claim, and desire to secure by Letters Patent, is—

The design for the handle of a spoon, 30 fork, or other article, consisting of the series of beads A, arranged on the face of the handle round its edge, the raised ribs B, extending longitudinally of the handle, the beads C, interposed between some of the longitudinal ribs, 35 and the shell-like ornament D at the upper end of the handle, substantially as shown and described.

WALTER WILKINSON.
